COMBINATION TRELLIS AND KNICK-KNACK SHELF

Jack V. Swartz, Chicago, Ill.

Application March 21, 1958, Serial No. 50,128

Term of patent 14 years

(Cl. D33—3)

FIG. 1

FIG. 3

FIG. 4

Fig. 1 is a front elevational view of a combination trellis and knick-knack shelf embodying my new design; Fig. 2 is a top plan view thereof; Fig. 3 is a side elevational view thereof; and Fig. 4 is a bottom plan view thereof.

I claim:

The ornamental design for a combination trellis and knick-knack shelf, as shown.
